COMBINED FLUID DISPENSER WITH BRUSH FOR
CLEANING UPHOLSTERY OR THE LIKERobert A. Yonkers, Grandville, Mich., assignor to Bissell
Inc., Grand Rapids, Mich., a corporation of Michigan

Filed July 26, 1968, Ser. No. 12,913

Term of patent 14 years

Int. Cl. D4—01

U.S. Cl. D4—7

FIGURE 1 is a perspective view of a combined fluid dispenser with brush for cleaning upholstery or the like which embodies my new design;

The dominant features of my design reside in the portions shown in full lines.

I claim:

The ornamental design for a combined fluid dispenser with brush for cleaning upholstery or the like, substantially as shown and described.
